UNITED STATES PATENT OFFICE

JOHN D. LEMEX, OF TULSA, AND DEWEY R. SMITH, OF ARDMORE, OKLAHOMA, AS-SIGNORS, BY MESNE ASSIGNMENTS, TO OIL WELL SUPPLY COMPANY, OF PITTSBURGH, PENNSYLVANIA, A CORPORATION OF NEW JERSEY

SAND CAP

Application filed June 13, 1928. Serial No. 284,920.

Our invention relates to a new and improved cap especially designed for use on a stuffing-box employed at the upper end of the tubing when pumping wells, and more particularly to a sand cap for a stuffing-box of the character specified, of simple and efficient construction that may be readily applied to a stuffing-box of the usual type.

In stuffing-boxes of this class, as is well known, an oil reservoir is provided for properly lubricating the polish rod which passes therethrough during the pumping operation. In the use of these stuffing-boxes as heretofore constructed, especially in localities where dry weather and high winds prevail most of the time, fine sand and other foreign matters, which have a severe cutting effect, accumulate in the oil reservoir and other parts of the boxes, causing wear and destruction of the operating parts and necessitating frequent shut-downs.

Among the objects of the present invention are: to provide a cap that may be readily applied and of a construction that will prevent the entrance of sand and other foreign matter to the box and prevent the escape of oil therefrom; to provide a cap in the form of an attachment for the stuffing-box capable of application thereto without stopping the pumping operation; and to provide a cap of an inexpensive and durable construction including novel separable or displacable sections adapted to interfit with the upper portion of the stuffing-box.

Various additional objects and advantages will become apparent from a consideration of the description following taken in connection with the accompanying drawings illustrating one practical embodiment of the invention.

In said drawings:

Fig. 1 is a plan view of our improved cap;

Fig. 2 is an elevational view looking toward the wall of one of the sections which is adapted to contact with the other section;

Fig. 3 is a sectional view taken on the line III-III of Fig. 1;

Fig. 4 is an elevation, partly broken away, showing the sand cap in place on the stuffing-box and a portion of the tubing; and

Fig. 5 is a sectional view taken on the line V-V of Fig. 4.

Referring specifically to the drawings, wherein like reference characters designate like or similar parts, 10 designates a conventional stuffing-box of the type designed to be mounted at the top of the well tubing 11, and through which a polish rod 12 reciprocates, as usual. The stuffing-box shown has a lubricant reservoir for lubricating the polish rod 12; handles 13, and flanges 14 at its top, as usual.

In carrying out our invention, a cap, generally designated 15, is used. Such cap consists of a plurality of independent, separable or displacable sections, for instance, two sections 16, as shown in the drawings. Such sections meet on a vertical diametric plane, as at 17, and at the top, the sections have oppositely extending lateral flanges 18 disposed in correspondingly shaped recesses 19 of the companion section.

The sections, when assembled, provide a bore opening 20, through which the polish rod 12 passes, and such bore is enlarged to form an annular groove or recess 21 in which rubber or other packing elements 22 are removably disposed. Said packing elements 22 fit and wipe the periphery of the polish rod 12 as the latter reciprocates through the stuffing-box and cap.

Adjacent the bases of the sections 16, receiving grooves 23 are provided, affording flanges 24 directly below the same. Said grooves 23 receive the flanges 14, which latter are overlapped from below by the flanges 24 so that the cap is engaged with the stuffing-box against danger of vertical movement relatively thereto. Between the flanges 24, cut-away portions or slots 25 are provided, in which the upper portions of the handles 13 are disposed, whereby the sections 16 cannot be turned relatively to the stuffing-box. It will be understood that, in applying the sand cap to the stuffing-box and polish rod, the sections 16 are in separated relation and are individually positioned.

The sections 16 are held together in unitary relation against lateral or radial displacement by means of a contractile steel ring 26, 100

entered in registering grooves 27 provided peripherally of the sections 16.

It will be noted that the cap 15, especially due to the intimate contact of the packings 5 22 with the polish rod 12 and the sections 16 generally closing the top of the stuffing-box 10, protects the lubricant within the stuffing-box against the entrance of sand or foreign matter whose abrasive effect on the 10 working parts would cause rapid wear thereof, frequent repairs and replacements, attended by shut-downs in operation.

Channels or grooves 28 of sections 16 are in communication with the central opening 15 20 to enable the wipings from the polish rod, and other collected foreign matter, to be carried away from said rod.

In addition to excluding foreign matter from the working surfaces, the packing 22 20 serves to maintain the lubricant within the stuffing-box or against rising on the up-strokes of the polish rod. At the same time, the improved sand cap may be readily applied even while the well is pumping, and is 25 of a construction that is inexpensive and exceedingly durable.

The sand cap is especially useful in the oil fields of western Texas and Oklahoma, which experience many and long periods of 30 dry weather and high winds, which set a fine sand into circulation in the air, and which accumulates in the lubricant reservoirs of stuffing-boxes and at the zones of contact of working parts.

35 Various changes may be resorted to, provided they fall within the spirit and scope of the invention.

What we claim is:—

40 A sand cap for the purpose specified having a bore therethrough, said cap being in separable sections, said bore being enlarged to form a groove, packing disposed in said groove for engagement with a polish rod, said cap below said groove having a depending marginal flange adapted to surround the stuffing-box below its upper end, said bore being further enlarged to provide a recess adapted to receive parts of a stuffing-box for 45 attachment of the cap thereto, a contractile ring securing said sections together, said sections adjacent the top having oppositely extending lateral flanges, and the sections having recesses receiving said latter flanges.

50 In testimony whereof we affix our signatures.

JOHN D. LEMEX.
DEWEY RAY SMITH.
